UNITED STATES PATENT OFFICE

2,672,231

CONTROL UNIT FOR COMPOSING MACHINES

Maurus T. Goetz, Chicago, Ill., assignor, by mesne assignments, to Teletypesetter Corporation, Chicago Ill., a corporation of Delaware

Application May 6, 1952, Serial No. 286,403

10 Claims. (Cl. 199—18)

1

The present invention relates to improvements in line casting and composing machines and more particularly to automatic control mechanisms therefor.

In general the present invention features an automatic control mechanism applicable to standard types of line casting machines without changing the manual operating features and retaining other characteristic features of these machines.

The principal object of the invention is to provide in an automatic control mechanism for composing machines a selector mechanism featuring an improved type of selector bar assembly which is conducive to high speed operation.

Another object of the invention is to provide in an automatic control mechanism for line casting and composing machines, a selector mechanism of improved type including an additional codal overlap to provide a more facile two-cycle system of operation of these machines.

Specifically, the unit is controlled by a perforated control form or tape which may be prepared by the operation of a machine such as disclosed in Patent No. 2,059,250, granted November 3, 1936, to H. L. Krum, and which if fed through a record reading device wherein there is provided a plurality of feeler members, each one of which corresponds to a position in the tape that may or may not be provided with a perforation depending upon the particular code combination that is being read or sensed. Upon each momentary arrest of the control form the several feelers sense the code combination perforated in the particular position and upon the next movement the combination is transferred to an intermediate set of storage devices following which a set of code bars are also positioned in accordance with such code combination. The code bars are provided with notches on both top and bottom edges thereof and in this manner they accommodate a double alignment of selectable elements. In the preferred practice of the present invention the selectable elements are alternately and oppositely disposed with respect to each other in scissors-like fashion constituting two rows which are movable toward each other when urged into selected position. For each permutation of the code bars one and only one of these selectable elements may be placed into selected position and when any particular one is thus selected it actuates an associated interponent member to a position between an intermittently operated striker bar and a corresponding one of a plurality of keylever actuators. With the structure

2

according to the present invention the interponents are actuated by the selectable elements into the path of the striker bar which then seizes control of the interponents to permit the selectable elements to respond to the succeeding selection thus providing an overlap. The motion of the common striker element is imparted through a keylever actuator to the particular keylever as a sharp staccato blow simulating the "touch" of the operator's finger when it is manually operated. A cam shaft which is constantly rotated during the normal operation of the record reading device serves to reset the selectable elements and also to actuate the common striker bar and is timed with respect to the operative cycle to perform two complete selective functions for each revolution.

It is thus an important feature that by virtue of the fact that all of the necessary functions are accomplished within a half revolution of the primary driven shaft, the speed of the driving elements can be enhanced because with the arrangement according to the present invention an additional codal overlap is provided.

25 A better understanding of the present invention will be obtained from the following description taken in conjunction with the accompanying drawings wherein:

Fig. 1 is a transverse sectional view through the keyboard and matrix release mechanism of the composing machine illustrating the selector mechanism according to the present invention;

Fig. 2 is a detail sectional view illustrating an initial or selection stage in the automatic operation of a keylever;

30 Fig. 3 is a detail sectional view illustrating the operational stage in the automatic operation of a keylever; and

Fig. 4 is a longitudinal cross-sectional view 35 through the record reader mechanism and associated parts.

40 Since the disclosure herein set forth is in the nature of an improvement of the control unit disclosed in U. S. Patent No. 2,091,286 issued August 31, 1937, to H. L. Krum et al., only so much of the mechanism of the patented structure will be hereinafter set forth as is necessary to an understanding of the present invention. Reference may be had to said patent for a full 45 understanding of the control unit not described hereinafter in detail.

Having reference to Fig. 1, wherein is shown a cross-sectional view of a line casting and composing machine embodying a control unit according to the present invention, there is pro-

vided a main framework 21 (of the control unit), more fully described in said Patent No. 2,091,286, and which is mounted beneath the standard keyboard 22, customarily provided with line casting and composing machines, in a manner indicated in said Patent No. 2,091,286. While in the case of the majority of the weight bars 23 there is provided not only a manually operated keylever 24 but also an independent automatically operated lever 27, it will be noted that this is not true in the case of those characters whose manually operated keylevers are situated in the lower two rows of the six horizontal rows of keylevers. In the case of these two rows of keylevers, instead of providing separate automatically operated levers 27, each keylever 24 has been modified by the addition thereto of an offset portion 26 generally similar to the corresponding portions 26 of the keylevers 27, but in this case integrally formed with the manually operated keylevers.

Referring now to Fig. 1, wherein a typical cross-section through the selector and matrix release mechanisms is indicated, attention is directed to the standard keyboard construction in particular contemplation of which this structure has been designed. Keylevers 24 pivoted on shafts 25 are suitably articulated to move members or weights 23 as at 29 admitting of considerable lost motion at their several points of articulation by virtue of excess clearance 31. A particular "touch" is obtained by providing a uniform leverage ratio in all of the keylevers, although, as is readily seen, each horizontal row proceeding downwardly is progressively longer than its preceding one. The weights 23 are provided with several notches 31 so as to be adaptable to standard replacement in connection with other of the several keylevers. Additional keylevers 27 pivoted at 32 are mounted for engagement with the lowermost notch 31 of certain of the several weights 23 and are provided with offset extensions 26 that protrude through a panel 33 of the keyboard. Thus, it will be seen that as to the release of matrices controlled by keylevers in the upper four rows, Fig. 1, either the manual control levers 24 or the automatic control levers 27 may be operated independently and that in so doing, the other or unoperated of the two remains inert and does not in any way enter into motion either associatively or collaterally, but as to the release of matrices controlled by the keylevers in the lower two rows a single lever is utilized for operation both manually and automatically.

An alignment of bell crank levers 35 fulcrumed on a common shaft 36 is disposed to overlap the aforementioned extensions or portions 26 so as to engage them when rotated clockwise and against the action of individual springs 37. The vertical arms 38 of the bell cranks 35 register opposite certain ones of a corresponding plurality of interponents 39 of the improved selector mechanism 40, according to the present invention, the operation of which is controlled in the following manner.

Having reference to Fig. 4, there is shown a record reader, indicated generally as 41, which through a transfer mechanism 42 controls the permutative setting of a series of intermediate bars 43, which in turn control the permutative setting of a series of permutation code bars 44. Code bars 44 control the selection of a group of selectable bars 45 which in turn control the in-

terponents 39 to effectuate the selective operation of bell cranks 35.

The record reader 41 comprises a set of feeler levers 46 (six in the present instance), so called because of their function in sensing the attributes of a transverse line or row of tape perforations. Levers 46 are provided with arms 47 which carry feeler or sensing pins 48, and are also provided with projections 49 serving to be engaged by a bail 51 for periodically withdrawing the levers 46 in accordance with each successive reading or sensing of the record or control tape. The bail 51 moves as part of a bell crank structure 52 which also is actuated by the shaft 53 through a cam 54 and roller 55.

Feeler levers 46 are each provided with a pair of depending portions 56 and 57 and counterclockwise bias is normally imparted to levers 46 by individual springs 58. Portions 56 and 57 are adapted to cooperate with a pair of abutments 59 and 61 on associated ones of a corresponding series of transfer T-levers 62 mounted pivotally on a pivot stud 63 fixed to one arm of a bell crank lever 64 pivoted at 65, the short arm of which abuts a short arm of another bell crank lever 66 also pivoted at 65, the other end of which carries a roller 67 spring urged by a spring 68 to follow the peripheral surface of a cam 69 secured to the shaft 53.

The abutments 59 and 61 are so spaced apart that when either of the two portions 56 or 57 is brought into registration with its associated abutment 59 or 61 the other of the shoulders or portions 56 or 57 just clears its associated abutment 59 or 61 on T-lever 62. Feeler levers 46 are provided with an intermediate orifice 71 having sufficient clearance with respect to a fixed rod 72 positioned thereinto so as to permit of a slight reciprocative motion by the levers 46. In its limit of movement each feeler lever 46 may be positioned so that one or the other of its shoulders 56 or 57 is brought into register with its associated abutment 59 or 61. The cam 69 has a gradually ebbing apex and when it is rotated together with its shaft 53 it imparts a regular and reciprocating motion to the lever 64—66 and associated T-levers 62.

T-levers 62 are provided with disc portions 73 by means of which they are articulated to bars 43 through slots 74. Bars 43 are in turn provided with projections 75 through which they are articulated to code bars 44. Thus, it will be seen that in accordance with the timed action of bell crank 52 and lever 64—66 the set of feelers 46 will first be permitted to rotate counterclockwise during which time those whose pins 48 are not blocked by the tape 76, but which are brought into registration with a perforation thereof, will be permitted to rotate until their respective shoulders 57 register opposite the abutment lugs 61 while the others which are not permitted to do so will remain in position with their shoulders 56 in registration opposite the abutment lugs 59.

Immediately following this condition, the cam 69 moving lever 64—66 counterclockwise forces the several T-levers 62 into engagement with their respective feeler levers 46 and, depending upon which of the two positions the feeler levers happen to assume, T-levers 62, upon being rocked about pivot 63, will be correspondingly positioned and will impart a similar position to their associated bars 43. In this manner the combination of perforations present in each transverse alignment in the tape is trans-

lated simultaneously to the six code bars 44. Following each such translation the tape 16 is stepped forward until another transverse alignment of perforations is brought into registration with the feeler pins 48. This stepping is accomplished by a pawl 17 and ratchet wheel 78 under the control of a cam (not shown) on shaft 53, in a manner disclosed in the aforesaid U. S. Patent No. 2,091,286. The ratchet wheel 78 is secured to a shaft 79 which also carries a sprocket wheel 81 having teeth especially adapted to register with the central longitudinal row of perforations of the control tape in accordance with the well known practice. In this manner, the single shaft 53 operates all of the mechanical agencies that control the record reader mechanism.

Particular attention is directed to the fact that while the several feeler levers 46 are brought back to a normal or starting position at some definite point in each cycle of operation, yet the transfer levers 62 and their articulated slide bars 43 are not so restored, but may be set in conformity with a new code combination regardless of their previous position. This practice permits of an overlap in the operation of the two sets of levers and allows the code bars 44 maximum time of rest during each cycle of operation.

Referring to Fig. 1, the code bars 44, as previously mentioned, are provided with notches on both top and bottom edges thereof, and in this manner they accommodate a double alignment of selectable elements 45 which are mounted pivotally on a common pivot 86. Confronting pairs of selectable elements 45 are normally biased toward each other by a common spring 87. Elements 45 normally tend to move into selective engagement with the code bars 44 but are restrained therefrom by a spreader cam shaft 88, as set forth in said U. S. Patent No. 2,091,286. Cam shaft 88 is provided with two longitudinal cam surfaces 89 and in rotating counterclockwise, during each half revolution thereof, the shaft 88 tends to spread the selector bars 45 and then to permit them to approach each other. The surfaces or apices 89, while at rest and holding apart the selectable bars 45, cause the latter to clear the edges of the permutation code bars 44, as indicated in Figs. 1 and 3, but immediately after leaving this position, and during rotation, as indicated in Fig. 2, the several selectable bars 45 are permitted to approach each other and to contact the edges of the set of permutation code bars 44 and for each permutative condition of the several code bars 44, an individual alignment of notches is afforded into which the adjacent selectable bar 45 is permitted to drop, as is well known in the art. As indicated in Figs. 1, 2 and 3, notches 91 located in bars 45 are provided adjacent the spreader cam 88, so as to permit a sudden drop by a selectable bar 45 when the cam portion 89 passes under it. This practice allows greater time for the selectable bars 45 to be disposed in position for operation and also hastens its presentation therewith relative to an operative cycle.

Cooperating with the free extremities of the selector bars 45 are a group of interponents 39 rockably mounted on a common pivot shaft 92. Each interponent 39 has a tail portion coacting with the extremity of its companion selectable bar 45, and a hook or shouldered portion 93 cooperable with a reciprocating striker bar or common actuator 94. The movement of the several selectable bars 45 is defined by the elongated

slots 95 which straddle the common shaft 92. The interponents 39 are normally biased by individual springs 96 so that their hook portions 93 are out of cooperable engagement with actuator 94 and their tail portions are in cooperative relation with the extremities 91 of selectable bars 45. Upon selection of a selectable bar 45 in the manner previously described, the foremost portion 97 thereof either of the upper alignment or of the lower one, as the case may be, functions to rock its associated interponent against the action of spring 96 to position the shoulder 93 thereof into the path of the striker bar 94 so that the operated interponent may be engaged by said bar 94. When the striker bar 94 moves leftwardly, it engages the shoulder 93 of the interponent 39, as viewed in Fig. 3, and carries the interponent 39 bodily with a sharp staccato motion, driving it against the lower arm 38 of its associated bell crank lever 35, causing said lever 35 to be sharply actuated clockwise against the pull of spring 37 to depress the end 26 of lever 27 to, in turn, raise the weight 23 articulated thereto to operate the trigger 101 to initiate the matrix selection function, as will presently appear.

In accordance with the present invention, a salient feature thereof is the provision of a further codal overlap in the operation of the selector mechanism, whereby the speed of operation of the line composing machine is greatly enhanced. To achieve this additional overlap, the interponents 39 are provided by means of which the two functions; namely, selection of bar 45 and operation of bell crank 35 are merged substantially into the same time interval, instead of occurring successively as heretofore in the prior art structures. Thus, with this improved overlap arrangement, the succeeding selecting of a bar 45 is permitted while an interponent 39 in response to the previous selection is being operated or actuated by the striker bar 94. Moreover, the speed of operation is enhanced, since the striker bar load is reduced greatly because said striker bar need only operate a light weight member like the interponent 39 instead of a heavier element like the selectable bar 45 of the present structure or the analogous bars of the prior structure shown in patent No. 2,091,286.

Although the selector mechanism according to the present invention has other applications, it is disclosed in the preferred embodiment shown in Fig. 1, as incorporated into a line casting and composing machine having a matrix release mechanism controlled by the record reader 41 (Fig. 4) through the selector mechanism 40 (Fig. 1). The operation of any of the weights 23, either through the medium of the manually controlled keylever 24 or through the automatically controlled lever 27, results in releasing a corresponding one of a plurality of time delay mechanisms. This is accomplished by rotating trigger 101 counterclockwise until it ceases to support its cam yoke 102 whereupon the latter member drops until the peripheral teeth 103 of cam 104, which is pivoted between the tines of said yoke, engage a continuously rotating rubber roller 105. The engagement between the teeth 103 and the roller 105 imparts a clockwise motion to the cam 104 which, on account of its eccentricity raises yoke 102 until its remote end 106 abutting a release reed 107 imparts a timed stroke through the matrix release mechanism, illustrated generally at 108, whereupon it is again

supported by the trigger 104 pending another release movement.

The purpose of the timed release mechanism, as is generally known, is to permit of sufficient time in the magazine trip 108 without having to expend the same amount of time in depressing a control key 24 or 27. The imperativeness of such an element of delay is made of principal importance in view of the fact that the matrices are released and allowed to gravitate into assembled relation, for without such, and particularly under the speed of automatic control, a direct release means might be actuated and be restored to normal position before its matrix has had time to move from its magazine 109. One of these overlap mechanisms is provided with each of the levers 27 whose function it is to release a matrix 111 from the magazine 109.

Of the several code bars 44 in the present embodiment (Fig. 1), six of them are positioned in each cycle of operation through the agency of the record reader mechanism 41, while a seventh code bar 99, called the shift code bar, is positioned or shifted under the control of the code bars 44, as fully described in said U. S. Patent No. 2,091,286. Although six code bars 44 are contemplated in the present disclosure, it is understood that any number of code bars may be employed to suit the desired selective possibilities.

It is to be understood that the above-described arrangement is merely illustrative of the application of the principles of the invention. Numerous other arrangements may be readily devised by those skilled in the art which will embody principles of the invention and fall within the spirit and scope thereof.

What is claimed is:

1. A control unit including a set of permutation bars having double edged code notch accommodations, a plurality of pairs of attrahently biased members having confronting edges cooperable with respective ones of said code notch accommodations, a spreader interposed to block selective response of a selected member for a predetermined interval when said bars are positioned to allow its selective freedom and to permit said response after the transition of a predetermined interval, a plurality of interponents each responsively associated with a selectable member, and a reciprocating operating bar, said interponents having facilities engageable with said operating bar, whereby upon a selective response of said members a companion interponent is brought into engaging relation with said operating bar to initiate functional operations.

2. A control unit including a set of permutation bars having double edged code notch accommodations, a plurality of members individually selectable in accordance with the positionment of said bars and oppositely disposed in accordance with said double edged accommodations, spring elements for urging said members against said bars, a cam for cyclically withdrawing said members from said bars, a reciprocating actuator bar, a plurality of interponents each responsively associated with a selectable member, said interponents having engaging facilities, whereby said actuator bar is adapted to engage a selected interponent.

3. In combination in a selector mechanism, a plurality of operable elements, a plurality of selectable elements arranged in two rows, a set of permutative selector bars between said rows, signal controlled means for variously positioning said bars to effect the individual selection of said

elements, means for attrahently biasing said selectable elements, spreader means interposed between said rows to effectuate the actuation of said selectable elements toward and away from

5. said permutation bars, a plurality of tailed hook members arranged in two groups corresponding to said rows of selectable elements and provided with confronting hook portions, said tail portions operably associated individually with the extremity of a companion selectable element, and a reciprocating bail adapted under predetermined operating conditions to cooperate with said confronting hook portions, whereby upon selection of a selectable element under the control of said spreader means said bail is effective upon the hook portion of a hook member which has been operated by its companion selectable element to operate one of said operable elements.

4. In a line composing machine, a keyboard 20 comprising a plurality of keylevers arranged in rows for manual operation, a corresponding plurality of selectable elements for automatically operating said keylevers, said elements alternately and oppositely staggered and disposed below 25 said keylevers, a set of permutation bars between the alternate alignments of said elements severally positionable for individually selecting said elements, a corresponding plurality of interponents mounted on a common pivot and individually related cooperatively to said selectable elements, a common actuator for said interponents, and means for moving each selector element towards said bars upon its selection to condition its associated interponent for actuation by said 30 common actuator, whereby an associated one of said keylevers is actuated.

5. In a selector mechanism, a plurality of instrumentalities to be actuated, a plurality of pairs of attrahently biased selectable elements, 40 a set of permutative selector bars having double-edged code notch accommodations, said selectable elements having confronting edges cooperable with respective ones of said code notch accommodations, signal controlled means for variously positioning said bars to effect the individual selection of said elements, a spreader interposed between the members of said pairs to block the selective response of a selected element for a predetermined interval when said bars are positioned to allow its selective freedom and to permit said response after the transition of a predetermined interval, a reciprocating striker bar, and a plurality of dually movable members, mounted for rotary and reciprocatory movement on a common shaft, each member having a hook portion cooperable with said striker bar and a tail portion cooperable with said selectable element, said hook portion adapted to be interposable between said striker bar and an instrumentality, and said tail portion cooperable with said selectable elements, whereby said selectable element when selected is effective through said tail portion to present said interponent portion into the path of movement of said striker bar to actuate an associated instrumentality.

6. In combination, a plurality of instrumentalities to be actuated, a set of permutation bars having double edged code notch accommodations, a plurality of pairs of attrahently biased members having confronting edges cooperable with respective ones of said code notch accommodations, spreader means interposed between the members of said pairs to effectuate the actuation of said members toward and away from 70 said permutation bars, a plurality of inter-

ponents each responsively associated with a member, and an operating bar, said interponents having facilities engageable with said operating bar, whereby upon a selective response of said members a companion interponent is brought into engaging relation with said operating bar to actuate an instrumentality.

7. In combination, a plurality of instrumentalities to be actuated, a set of permutation bars having double edged code notch accommodations, a plurality of pairs of attrahently biased members having confronting edges cooperable with respective ones of said code notch accommodations, spreader means interposed between the members of said pairs to effectuate the actuation of said members toward and away from said permutation bars, a striker bar, and a plurality of elements mounted on a common shaft, each element having an interponent portion cooperable with said striker bar and a tail portion cooperable with said members, said interponent portion adapted to be interposable between said striker bar and an instrumentality, and said tail portion cooperable with said members, said members when selected being effective through said tail portion to present said interponent portion into the path of movement of said striker bar, whereby an associated instrumentality is actuated.

8. In combination, a plurality of instrumentalities to be actuated, a tape reader, a set of permutation bars having double edged code notch accommodations, a transfer device for transferring the reading of said tape reader to said set of permutation bars, a plurality of pairs of attrahently biased members having confronting edges cooperable with respective ones of said code notch accommodations, spreader means interposed between the members of said pairs to effectuate the actuation of said members toward and away from said permutation bars, a plurality of interponents each responsively associated with a member, and an operating bar, said interponents having facilities engageable with said operating bar, whereby upon a selective response of said members a companion interponent is brought into engaging relation with said operating bar to actuate an instrumentality.

9. In combination, a plurality of instrumentalities to be actuated, a set of permutation bars having double edged code notch accommodations, a plurality of pairs of attrahently biased

members having confronting edges cooperable with respective ones of said code notch accommodations, spreader means interposed between the members of said pairs to effectuate the actuation of said members toward and away from said permutation bars, a plurality of interponents having two different kinds of motion, each interponent responsively associated with a member, and a reciprocating operating bar, said interponents having certain facilities responsive to the selective movement of said members to impart one kind of motion to said interponents, and other facilities engageable with said operating bar to impart another kind of motion to said interponents, whereby upon a selective response of said members a companion interponent is brought into engaging relation with said operating bar to actuate an instrumentality.

10. In combination, a plurality of instrumentalities to be actuated, record reading means, a set of permutation bars having double edged code notch accommodations, means for transferring the selective condition of said record reading means to said permutation bars, a plurality of pairs of attrahently biased members having confronting edges cooperable with respective ones of said code accommodations, spreader means interposed between the members of said pairs to effectuate the actuation of said members toward and away from said permutation bars, a plurality of interponents having two different kinds of motion, each interponent responsively associated with a member, and a reciprocating operating bar, said interponents having certain facilities responsive to the selective movement of said members to impart one kind of motion to said interponents, and other facilities engageable with said operating bar to impart another kind of motion to said interponents, whereby upon a selective response of said members a companion interponent is brought into engaging relation with said operating bar to actuate an instrumentality.
